Domestic Spinning
Patented Dec. 14, 1812.

~William M. Peabody
Bitter Patent

850X

The article referred to in the Bitter Patent and making part of the same containing a description in the words of the late William M. Peabody himself of the improvement in the construction of Wheel heads.

The wheel on the Spindle very much with a large whell between the spindle and the wheel and the band to crop between the wheel and the first whell and also crop again between the first whell and the whell which turns the spindle. The great improvement in this construction compared with any other contrivuted wheel head, is that the band cropping so near the whell which turns the spindle it touches the surface of the spindle whell nearly round consequently the spindle which may be made so small that turning of the spindle may be accelerated nearly one hundred fold compared with the usual contrivuted wheel head and the band must be cropt twice that the spindle may turn the whell may.

Witnesses,

Joseph D. Weston
Nathan Boston
